UNITED STATES PATENT OFFICE

JOSEPH J. WARREN, OF PITTSBURGH, PENNSYLVANIA

TUNING DIAL FOR RADIOS

Application filed April 17, 1931. Serial No. 530,827.

This invention relates to tuning dials for radios, and in particular to improvements in the drum carrying the station markings and the window through which the markings are viewed, and is a continuation in part of my pending application, serially numbered 504,883, filed December 26, 1930.

It is an object of this invention to provide a dial or drum having station markings arranged thereon in such a manner that they can be easily read and a greater number of characters can be placed on the dial than is possible with the dial now in use.

Another object of this invention is to provide means to successively position the station markings arranged spirally on a drum in a window when the drum is rotated.

A further object of this invention is to provide a window having a shutter arranged thereon in such a manner that it is moved lateral on rotation of the drum.

These and other objects which are readily apparent to those skilled in this particular art are accomplished by means of this invention, one embodiment of which is described in the following specification and illustrated in the accompanying drawing, wherein;

Figure 1 is a fragmentary sectional view through a radio device showing the invention.

Fig. 2 is a view in section taken on line II-II of Figure 1.

Fig. 3 is a view in section taken on line III-III of Fig. 2; and

Fig. 4 is a partial view in front elevation of the radio cabinet.

Referring to the drawing in detail, 10 designates a shaft journaled in brackets 11 which are secured to a portion of the radio device. One end of the shaft 10 is connected by gears 12 to a shaft 13 which extends through the front wall 14 of the radio device, and has a knob 15 secured thereto through which the shaft 10 is rotated. The other end of the shaft 10 is connected by suitable gearing (not shown) with a shaft which operates the tuning condensers with which it is synchronized. The shaft 10 has a circular disc 16 mounted thereon which forms the hub of a

tuning dial or drum 17 which carries the station markings or other indicating characters. The station markings are arranged in a spiral on the periphery of the drum so that greater space may be obtained between the station markings, consequently permitting the markings to be of larger size than is possible with the dial now in use, and making them readily visible. The station markings may be formed directly on the drum or on a tape wound in a spiral around the periphery of the drum.

The station markings or characters on the drum 17 are viewed through an opening or window 18 which is formed in the front wall 14 of the radio cabinet, and which extends the full width of the drum. In order that only one station marking will appear in the opening 18 at any one time, a shutter 19 is provided which has an opening 20 which registers with the opening 18 and of such width that one station marking only, on the drum 17, is visible at one time. The shutter 19 is slidably mounted in brackets 21 secured to the inner face of the wall 14.

In order that each of the spirally arranged station markings on the drum 17 may be successively viewed through the openings 18 and 20, the shutter 19 is provided with grooves 22 which receive a spiral rib 23 formed on the circumference of the drum. As the drum 17 is rotated in either direction, the ribs 23 impart lateral or endwise movement to the shutter 19 causing it to move back and forth across the window 18 and position the successive station markings or characters in the opening 20 of the shutter.

The drum 17 having the station markings arranged spirally thereon is transparent or translucent so that a lamp 24 positioned inside the drum behind the opening 20 in the shutter 19 will illuminate the characters as they appear in the window and make them radially visible to the operator.

The lamp 24, which is movable laterally so that it will always be positioned behind the opening 20 in the shutter 19, is mounted in a plate 25 which is secured to a nut 26 carried on a sleeve 27 which is fastened on the shaft 10. The nut 26 has an internal

spiral thread 28 which meshes with an external spiral thread 29 formed on the sleeve 27 so that as the shaft 10 and sleeve 27 are rotated the plate 25 will be caused to move back and forth on the sleeve. A shaft 30 which is secured to one of the brackets 11 and extends through an opening formed in the plate 25 and prevents the plate from turning with the sleeve 27. The thread between the nut 26 and the sleeve 27 is so formed that the light 24 is always maintained in position behind the opening 20 in the shutter 19 therefor. As the drum 17 is rotated, the plate 25 will move longitudinally on the sleeve 27 and maintain the light 24 directly behind the opening 20 in the shutter 19 which is being moved laterally across the window 18.

While I have described one embodiment of my invention it is to be understood that this invention is not limited to the construction herein specifically illustrated and can be embodied in other forms without departing from the spirit of this invention or the scope of the appended claims.

What I claim as new and desire to secure as Letters Patent is:

1. In a radio device, the combination of a closure having a view opening there-through, a light emitting drum mounted for rotation within said closure and having station markings arranged spirally thereon, a source of light within said drum and opposite said view opening, and means for moving said light source lengthwise of said drum as the same is rotated.

2. In a radio device, the combination of a closure having a window formed therein, of a translucent drum mounted for rotation in said closure and having station markings spirally arranged thereon, ribs extending from the periphery of said drum, a shutter having an opening therein for viewing the marking on said drum, and provided with grooves therein for cooperating with the ribs on said drum, a source of light within said drum for illuminating the markings in said view opening, means for rotating said drum for causing lateral movement of said shutter relative to said window to successively position the spirally arranged markings in said view opening, and means associated with said drum for moving said light laterally.

3. In a radio device, a translucent drum mounted for rotation and having station markings spirally arranged thereon, a window through which said markings are viewed, a shutter for partially closing said window, a light for making visible the markings through said window, and means associated with said drum for causing lateral movement of said shutter and light relative to said window so as to view successively the spirally arranged station markings.

4. In a radio device, a rotatable translucent

drum, a light mounted in said drum, and means for causing lateral movement of said light relative to said drum on rotation of said drum.

5. In a radio device, the combination with a closure having a window formed therein, of a movable shutter for said window and having a view opening therein, a rotatable shaft in said closure, a source of light slidably mounted on said shaft and opposite the view opening in said shutter, a light emitting drum mounted on said shaft and surrounding said light and having characters spirally arranged thereon, one of which is visible through the view opening in said shutter, means for rotating said drum, means associated with said drum for moving said shutter across said window as the drum is rotated whereby said spirally arranged characters are successively visible through said view opening, and means associated with said shaft for moving said light source endwise on said shaft for maintaining the same opposite said view opening.

6. In a radio device, the combination with a closure having a window formed therein, of a movable shutter for said window and having a view opening therein, a source of light within said closure opposite the view opening in said shutter, a light emitting drum within said closure and surrounding said light and having characters spirally arranged thereon, one of which is visible through the view opening in said shutter, means for rotating said drum, means for moving said shutter across said window as the drum is rotated whereby said spirally arranged characters are successively visible through said view opening, and means for moving said light source as said drum is rotated so as to maintain the same opposite said view opening.

7. In a radio device, the combination with a closure having a window formed therein, of a movable shutter for said window having a view opening therein, a source of light within said closure opposite the view opening in said shutter, means for moving said shutter across said window, and means for moving said light source so as to maintain the same opposite said view opening.

8. In a radio device, the combination with a closure having a window formed therein, of a movable shutter for said window and having a view opening therein, a source of light within said closure opposite the view opening in said shutter, a light emitting drum within said closure and surrounding said light and having characters spirally arranged thereon, one of which is visible through the view opening in said shutter, means for rotating said drum, means for moving said shutter across said window as the drum is rotated whereby said spirally arranged characters are successively visible through said view opening, and said means including a

spiral rib formed on the periphery of said drum engaging grooves formed in said shutter, and means for maintaining said light source opposite said view opening as the same is moved to and fro across said window.

9. In a radio device, the combination with a closure having a window formed therein, of a movable shutter in said window having a view opening therein, a source of light with-
10 in said closure and behind said view opening, and means for moving said shutter and said light source relative to the window in said closure.

In testimony whereof, I have hereunto sub-
15 scribed my name this 15th day of April, 1931.

JOSEPH J. WARREN.
